BOILER CONSTRUCTION

Anthony J. Donohue, Philadelphia, Pa., assignee
to Simplex Gas Products Corporation, Philadelphia, Pa., a corporation of Delaware

Application January 31, 1933, Serial No. 654,506

11 Claims. (Cl. 122—210)

This invention relates to improvements in fluid-fuel-fired heating apparatus. This class of apparatus is now subject to stringent laboratory approval tests to insure the user safety from carbon monoxide poisoning. To meet these approval tests with heat absorbing structures heretofore used, over-ventilation and higher stack temperatures than necessary are resorted to in order to achieve high capacities without the formation of carbon monoxide. This practice, obviously, results in lower operating efficiencies.

The transfer of heat in apparatus of the class described, especially when using the usual type of Bunsen burners in a gas-fired boiler can be best effected by convection, for under the most favorable conditions, less than 15 per cent. of the total heat in the fuel will be transmitted from the flame to the heat-absorbing surfaces of the boiler by radiation. Some additional heat will be radiated from the carbon dioxide and water vapor molecules in the hot gases, but this amount is negligible due to the thin streams of gases used in order to promote the maximum heat transfer by convection. The quantity of heat transmitted by convection per unit of heat-absorbing area depends primarily on the number of molecular impingements of the hot flowing gases against the heat absorbing surfaces. Increasing the number of molecular impingements against the heating surfaces or decreasing the temperature gradient across the gas stream by increasing the number of impingements of hotter molecules against layers of cooler molecules near the heating surface increases the rate of heat transfer.

The molecules of hot flowing gases, unless restrained, tend to stratify in layers of varying temperatures generally parallel to the direction of flow with the hottest layers of molecules in the center or core of the stream. Due to their kinetic energy, the molecules vibrate within the flowing layers of the gas stream, colliding repeatedly with adjacent molecules at a speed dependent upon their temperature. The slower moving molecules of the cooler layers are next to the heat-absorbing surfaces, and the more rapidly vibrating molecules and hotter layers towards the center of the streaming gases. This results in a temperature gradient across the gas stream which is especially steep near the heat-absorbing surface. The sharp drop near the heat-absorbing surface has lead many investigators to believe that a so-called "dead film" or layer of inactive gas adheres to the heating surface and that this layer or film acts as a heat insulation to retard the flow of heat.

Abruptly changing the direction of flow of the gases by the use of baffles or staggered flue passages tends to eliminate stratification and promote scrubbing of the hot gases against the heating surfaces. Such means, however, reduce the capacity of the heating unit due to the high resistance they impose on the flowing gases, with the result that larger amounts of heating surface are necessary, leading to cumbersome units in an attempt to produce complete combustion at any definite capacity.

An important object of the present invention is the provision of a structure of this character in which the flueways are so constructed that an increase of molecular impingements is produced without imposing any appreciable resistance upon the convectional flow of the hot gases.

A further object of the invention is to provide an efficient absorbing structure capable of operating at high capacities with low stack temperatures and a minimum amount of excess air without the formation of carbon monoxide.

A further object of the invention is the provision of a novel and improved extended surface projection and method of arranging such surface projections upon the walls to increase the heating capacity thereof.

A still further object is to provide improved extended surface projections arranged to substantially prevent an undesirable flow of gases to the exits through uninterrupted inclined passages.

These and other objects I attain by the construction shown in the accompanying drawings wherein, for the purpose of illustration, I have shown a preferred embodiment of my invention and wherein:

Fig. 1 is a vertical sectional view through a boiler constructed in accordance with my invention;

Fig. 2 is a similar enlarged sectional view through adjacent sections illustrating the construction of the flueways;

Fig. 3 is an enlarged fragmentary section through one of the flueways on line 3—3 of Fig. 4;

Fig. 4 is a side elevation of one of the sections, the surface projections of the boiler being partially omitted;

Fig. 5 is a section on line 5—5 of Fig. 3;

Fig. 6 is a section on line 6—6 of Fig. 3; and

Fig. 7 is an enlarged detail elevation showing the surface projections.

Referring now more particularly to the drawings, the numeral 10 generally designates a suitable casing having arranged therein end sections 11 and a center section 12, each of said sections

110

11 and 12 having a water leg 13 extending to the bottom of the burner pit 14 of the boiler. Connecting the upper ends of each end section 11 and the center section 12 is a stack outlet 15, and 5 arranged between each end section and the center section is one or more intermediate sections 16. Suitable intake and flow connections between the sections 11, 12 and 16 are provided, as indicated on Fig. 4 of the drawings. Each of the 10 sections 11, 12 and 16 is narrowed at its lower end to produce a tapering introducing throat 17 for flueways 18 between the sections and each of the 15 sections has its side wall of slightly sinuous or zigzag formation with the peaks 19 of the angles between adjacent angularly related faces aligned 20 with similar portions of the adjacent or opposed section, with the result that a vertical series of Venturi-form flueway sections are provided. The 25 throats 20 of these Venturi-form flueway sections decrease in width from the bottom to the top of the flueway so that compensation is had for the contraction of the gases as a result of reduction 30 of temperature thereof.

The Venturi shape of the flueways tends to direct 35 a considerable part of the flowing gases normally flowing in the center of the flueway toward the heat-absorbing surfaces, due to the fact that the Venturi action tends to spread the gases outwardly after passage through the throat sections 40. This spreading and resultant contraction of the flowing gases resists the natural tendency of the gases to stratify in temperature layers parallel to their flow without, however, producing undue 45 turbulence and with a minimum resistance due to the well known characteristics of the venturi. In comparative tests, this form of flueway produced 50 far better results per unit of surface than a vertically-walled flueway. Careful experiments indicate that the angles of the Venturi flue-shaped sections should depart only a few degrees from the vertical if a maximum efficient effect 55 is to be attained. By making the venturi with relatively small entrance and exit angles and comparatively wide throats, the Venturi effect 60 is obtained without tendency to choking of the hot gases at the Venturi throats. The Venturi action further minimizes entrance and exit resistance to the flowing gases, especially reducing the 65 resistance imposed as the hot gases approach the flueways. The flueways, considered as a whole, while constantly varying in width, are neither tortuous nor sinuous, so the resistance set up by the flueway walls is reduced to a minimum. Equalization ports 21 may be formed in the intermediate sections 16 permitting transmission of 70 gases between adjacent flueways of the same unit of the boiler and will serve to further eliminate any tendency to choking. These ports are, preferably, located at the junction of the Venturi sections.

Having increased the number of heat molecules directed against the walls of the flueways, an additional amount of heating surface per unit area must be provided to absorb the increased heat 75 rendered available. To this end, I provide adjacent faces of the sections 11, 12 and 16 with extended surface projections 22. Such surface projections, where provided in a construction of this character, should be of a construction providing a relatively large heat-absorbing surface without 80 imposing appreciable resistance to the passage of the flowing gases. Furthermore, the projections should be so arranged that resistance to flow resulting from the arrangement is minimized without 85 the formation of direct passages either verti-

cal or inclined, along which the gases may move without contact with the surface projections. Such extended surface projections are more particularly illustrated in Figs. 4 to 7 of the drawings.

The extended surface projections, 22, are of modified slip-stream formation, each comprising a main body portion 23 and an elongated tail portion 24. The tail portion is reduced in thickness in relation to the main body portion and extends from the main body portion in the desired direction of flow of the gases; in the present instance, vertically. The main body portion 23 of the pin presents slightly angularly related upstream surfaces 25 which divide the gas stream and direct the divided stream to the rounded side surfaces 26 of the body. The tail portion serves, as in all slip-stream constructions, to prevent the formation of dead air pockets at the down-stream face of the pin and being elongated acts likewise as a straightening vane directing the gases in the desired vertical direction, thereby substantially preventing a "short circuiting" flow of gases in an inclined plane to the flueway exits. For practical reasons, the upper end portions of 100 the tails 24 are preferably decreased in height as indicated at 24-a, the connection of these low portions with the pin presenting a relatively sharply outwardly and downwardly sloping surface 24-b to avoid the collection of foreign 105 matter.

Due to the tendency of fluids, and particularly of gases, when contacting rounded surfaces to cling to and follow the contour of such surfaces, an ordinary rounded pin would have a tendency 110 to produce a vacuum pocket at the down-stream face thereof, which is prevented by the tail portion. The generally ovate cross section of the body in combination with the reduction in thickness of the tail portion permits a maximum efficient exposure of the body portion while retaining the function of eliminating eddy pockets. Gases, instead of eddying at the back of the pin, move along the sides of the tail portion transferring their heat thereto and are, by these tail 115 portions, directed against the main body portions of succeeding pins. It will be noted that, due to the reduced width of the tail portion with respect to the body portion, the surfaces of the tail and body portions meet at a reentrant angle, 120 with the result that the gases engaging the tail portion must change their direction to a certain extent. This causes a slight check in the movement of the gases and a further impingement of the gases against the surfaces of the pins. The 125 body portions 23 are of such width that no truly vertical gas escape passages are provided between the pins, and the tail portions 24 are of such length that diagonally vertical passages are substantially interrupted.

As nearly as can be determined, the passage of the gases is as indicated by the arrows of Fig. 5. Particular importance is attached to the fact that the pin arrangement leaves no uninterrupted vertical passages and substantially no inclined 130 passageways through which hot gases may escape to the stack outlets. Pins on opposing sides of the flueway are preferably arranged in staggered relation to one another and pins on the same side of the flueway are preferably arranged 135 in rows with the pins of one row staggered with relation to those of the preceding row. This arrangement eliminates sudden and unbalanced restrictions in volume of flueway, thereby minimizing resistance to the flowing gases.

Employing the construction herein disclosed, it is possible to operate apparatus of the class described, utilizing balanced draft only, at capacities slightly greater than one-quarter boiler horse power per square foot of flue-way surface while lowering the temperature of the flowing gases from approximately 2000 degrees F. at the point of entrance to the flueways to only 300 degrees F. at the stack outlet, showing a high ratio of heat transfer at high operating capacity. Further, the gases are discharged at this temperature free of carbon monoxide and with an unusually low percentage of excess air.

Since the construction illustrated is, obviously, capable of considerable modification without in any manner departing from the spirit of my invention, I do not wish to be understood as limiting myself thereto except as hereinafter claimed.

I claim:

1. In a boiler, a flueway the walls of which are provided with substantially horizontal rows of surface projections, the projections of one row being staggered with relation to those of the next row, said surface projections being streamlined in the direction of flow of gases in the flueway, the rows of projections at opposite sides of the flueway being staggered with relation to one another.

2. In a boiler, a flueway the walls of which are provided with substantially horizontal rows of surface projections, the projections of one row being staggered with relation to those of the next row, said surface projections being streamlined in the direction of flow of gases in the flueway, the tail portions of the projections of each row directing gases against the sides of the body portions of the projections of the succeeding row, the rows of projections at opposite sides of the flueway being staggered with relation to one another.

3. A flueway wall provided with surface projections, each surface projection comprising a body portion and a tail, said body portion being of generally ovate cross section with its longer axis transverse to the general line of gas movement through the flueway, the tail portion being relatively narrow and extending in the direction of movement of the gases, the tail portion being curvilinearly merged with the body portion.

4. A flueway wall provided with surface projections, each surface projection comprising a main body portion having rounded sides and an elongated tail portion of abruptly reduced width with respect to the body portion and curvilinearly joined to the body portion, said tail portion extending in the direction of flow of the gases in the flueway.

5. A flueway wall provided with surface projections, each surface projection comprising a main body portion having rounded sides and an elongated tail portion of abruptly reduced width with respect to the body portion, said tail portion curvilinearly joined to the body portion, said tail portion extending in the direction of flow of the gases in the flueway and being of reduced height with respect to said body portion.

6. In a boiler, a flueway having surface projections upon the walls thereof, said surface projections each comprising a main body portion

having rounded sides and an elongated tail portion of abruptly reduced thickness with respect to said body portion and curvilinearly joined thereto, said tail portion projecting in the direction of flow of gases in the flueway, said projections being arranged in rows, the rows of projections at opposite sides of the flueway being staggered with relation to one another, the projections of adjacent rows at the same side of the flueway being staggered with relation to one another.

7. In a boiler, a flueway having surface projections upon the walls thereof, said surface projections each comprising a main body portion having rounded sides and an elongated tail portion of abruptly reduced thickness with respect to said body portion and curvilinearly joined thereto, said tail portion projecting in the direction of flow of gases in the flueway, said projections being arranged in rows, the rows of projections at opposite sides of the flueway being staggered with relation to one another, the projections of adjacent rows at the same side of the flueway being staggered with relation to one another.

8. A flueway wall provided with surface projections, each surface projection comprising a body portion and a tail, said body portion being of generally ovate cross section with its longer axis transverse to the general line of gas movement through the flueway, the tail portion being relatively narrow and extending in the direction of movement of the gases, the tail portion being curvilinearly merged with the body portion.

9. A flueway wall provided with surface projections, each surface projection comprising a body portion and a tail, said body portion being of generally ovate cross section with its longer axis transverse to the general line of gas movement through the flueway, the tail portion being relatively narrow and extending in the direction of movement of the gases, the tail portion being curvilinearly merged with the body portion and being of reduced height with respect to the body portion.

10. In a boiler, a straight vertical flueway having surface projections upon the walls thereof, said surface projections each comprising a main body portion having rounded sides and an elongated tail portion of abruptly reduced thickness with respect to said body portion and curvilinearly joined thereto, said tail portion projecting in the direction of flow of gases in the flueway and a burner arranged beneath said flueway.

11. In a boiler, a straight vertical flueway the wall of which is provided with surface projections, said surface projections each comprising a body portion and a tail, said body portion being of generally ovate cross section with its longer axis transverse to the general line of gas movement through the flueway, the tail portion being relatively narrow and extending in the direction of movement of the gases, the tail portion being curvilinearly merged with the body portion, and a burner beneath said flueway.

ANTHONY J. DONOHUE.
